ARCHERY BOW REEL

Leonard S. Meyer and George A. Shira, Newark, Ohio, assignors, by mesne assignments, to Parallel Products Company, Columbia, S. C., a corporation of South Carolina

Application July 16, 1956, Serial No. 598,195

1 Claim. (Cl. 242—85.1)

Our invention relates to an archery bow reel. It has to do, more specifically, with a reel which is designed for attachment to an archery bow to hold a supply of line that is attached to the arrow to be shot from the bow in fishing or other sports.

One of the objects of our invention is to provide a bow reel which can be attached to the bow with ease and is so designed as not to interfere with the normal action of the bow.

Another object of our invention is to provide a bow reel which is of such a nature as to prevent fouling of the line as it is unreeled therefrom upon shooting of the arrow from the bow.

A further object of our invention is to provide a bow reel which is of such a nature that the turns of the line will unreel therefrom orderly and will not tend to pull therefrom in bunches.

Still another object of our invention is to provide a bow reel which has automatically releasing gripping means that prevents the line from unwinding until actual discharge of the arrow from the bow.

An additional object of our invention is to provide a bow reel which is of such a nature that when it is attached to a bow the line can be rewound thereon and associated with the gripping means with one hand so that the other will be free to hold the bow and arrow.

Various other objects will be apparent from the following description and the drawings.

In the accompanying drawings, we have illustrated the preferred embodiment of our invention. In these drawings:

Figure 1 is a side elevational view of an archery bow upon which our reel is mounted.

Figure 2 is a top elevational view of the reel.

Figure 3 is an edge view of the reel taken along line 3—3 of Figure 2.

Figure 4 is a diagrammatic view illustrating the angular relationship of the upper and lower edges of the reel.

Figure 5 is an enlarged view of the outer or forward portion of the reel illustrating the combination guide groove and grip slit formed therein.

Figure 5a is a fragmentary sectional view taken along line 5a—5a of Figure 5.

Figure 6 is a diagrammatic view illustrating the angular relationship of the bow reel relative to the arrow before being shot from the bow.

Figure 7 is a similar view but showing the relationship after the arrow has been shot from the bow.

With reference to the drawings, our bow reel is shown in detail in Figures 2 to 5, inclusive. It is made in one piece preferably from a soft plastic material such as vinyl plastic, or other rubber-like material capable of being molded. The molded material should have a durometer hardness of 30 to 90 for a purpose which will be described later.

The molded one-piece reel is of narrow elongated form in the vertical direction and consists of an at-

2

taching section 10, which has a flat bow-contacting surface 11, and an integral forwardly extending reel section 12 which is merged to the attaching section at the upper and lower chamfered corners 13. The section 12 is of considerably less vertical extent than the section 10 so that the upwardly and downwardly extending attaching ears 14 are provided for use in attaching the reel to the bow.

The side surfaces 15 of the bow reel are parallel but the upper and lower edges of the reel section 12 are not parallel. Thus, in the position shown in Figure 4, the lower edge 16 is perpendicular to the flat surface 11, as indicated by the broken line A, and the upper edge 17 is at a predetermined angle relative to the surface 11, as indicated by the broken line B, so that the reel section 12 is tapered forwardly. The axis of the taper is indicated by the broken line C. The edge 16 is normal to the surface 11 and the edge 17 is at an angle of 85 to 88 degrees relative to that surface. This angular relationship is very important and will be discussed more in detail later.

The forward end of the reel section 12 is provided with a forwardly opening combination guide groove and line gripping slit 18 (Figs. 2 to 5 and 5a) formed diagonally across it. The outer part of this groove is widened as indicated at 19 so as to guide a line into the slit 20 which is recessed rearwardly within the wide part of the groove. In practice the guide groove 18 is molded into the reel section 12 with a base conforming to the dotted line 21 in Figure 5 and then a cut is made down through the bottom of the groove to form a slit down to the line 22 which will be the base of the slit. It will be noted that the slit part is of tablike form with its smaller end forwardmost and, consequently, when the line is slipped back into the guide groove 18 it will readily slip therefrom into the smaller area forward end of the slit and gradually back into the larger area thereof where it will be effectively gripped.

As shown in Figure 1, the reel may be mounted on a bow 26 of any suitable type. It is mounted above or below the midpoint of the bow and the ears 14 may be taped to the bow as indicated at 25. If it is mounted above the midpoint of the bow, as shown in Figure 1, the angled edge 17 will be uppermost whereas if it is mounted below the midpoint such edge will be lowermost. However, in the following description it will be assumed that it is uppermost. The line 23 will have one end attached to the rear end of the arrow illustrated at 24 and its opposite end will be anchored to the bow or other member such as a float, boat, etc. so that when the line unreels it will be attached to something. The line 23 is wound on the reel section 12 and the portion adjacent the arrow is slipped into the guide groove 18 and finally is clipped into the slit 19 which will grip and retain it. Three or four feet of the line 23 should hang free to permit drawing of the arrow 24. Because of the provision of the particular type of guide groove 18, the line can be clipped into the slit 19 with one hand while the other holds the bow and arrow. Since the reel section 12 is soft, this permits the first layer of convolutions of the line to cut into the soft material thereby preventing the line from slipping off the tapered section 12 in bunches. Successive layers will wind on preceding layers and will thereby be prevented from pulling off in bunches so that there will be an orderly sequential unwinding. Also, because the attaching section 12 is of relatively soft flexible material, it will bend readily with the bow and will not interfere with the normal action thereof. Thus, it is important that this reel be molded from a material which will have a durometer hardness of 30 to 90 as indicated previously.

The importance of the angular relationship between

the edges 16 and 17 is illustrated in Figures 6 and 7. As indicated previously, the lines A and B which are extensions of the lower and upper edges 16 and 17, respectively, will be in angular relationship. The line A will parallel the line D which will be the direction of discharge of the arrow. Since the edge 17 is at a predetermined angle relative to the path of the arrow, there will be no tendency for the line to snag on the upper forward corner of the section 12 as it is unreeled from such section due to the flight of the arrow. We have found in actual practice that the angle of inclination or taper of the edge 17 should be 82 or 85 degrees relative to the vertical or surface 11 and that the lower edge 16 should always be at 90 degrees. When the arrow is discharged, as shown in Figure 7, and moves into successive positions the line 15 23 will pay off the reel section 12 and the angle between the line 23 itself and the path of the arrow will decrease so that the tendency to snag will be lessened. Thus, the angular relationship between the edges 16 and 17, as represented by lines A and B, is more important in the initial 20 discharge of the arrow to prevent snagging.

It will be apparent from the above description and the drawings that our bow reel has a number of advantages. Some of the advantages have been discussed above and others will be apparent.

Having thus described our invention, what we claim is:

An archery bow reel comprising an integral tapered forward reel section and an attaching rear section, said tapered reel section extending forwardly having substantially parallel side surfaces and narrowing in a vertical direction towards its forward end to provide angularly 30

related upper and lower edges, the edge adapted to be disposed adjacent to the arrow rest of the bow being substantially normal to the vertical and the opposite edge being angled forwardly and inwardly relative to the vertical so that there will be no tendency for the line to snag on the forward end of the tapered section as it is unreeled from such section due to the flight of an arrow attached to a line to be wound on said tapered section and shot from a bow on which said reel is to be mounted adjacent the arrow rest thereof and with its angled edge disposed outwardly away from the arrow rest, the forward end of said tapered section having a guide groove therein extending transversely at an angle thereto having an outwardly opening mouth and communicating at its base with the outwardly opening mouth of a line gripping slit of less width than the groove, said slit being formed in a tab-like outward projection at the base of the groove so that the slit gradually increases in transverse extent from its mouth to its base.
